Patented Nov. 4, 1919.

UNITED STATES PATENT OFFICE.

HENRY W. TOMLINSON, OF CHICAGO, ILLINOIS.

METHOD OF BUILDING FOUNDATIONS.

1,320,720.

Specification of Letters Patent.

Patented Nov. 4, 1919.

Application filed October 21, 1918. Serial No. 259,123.

To all whom it may concern:

Be it known that I, HENRY W. TOMLINSON, a citizen of the United States, residing at Chicago, in the county of Cook and State 5 of Illinois, have invented a new and useful Improvement in Methods of Building Foundations, of which the following is a specification.

My invention relates to certain new and 10 useful improvements in the method of building foundations, and is fully described and explained in the specification and shown in the accompanying drawings, in which:—

Figure 1 is a transverse section through a 15 wall, the foundation for which is built in accordance with my invention; Figs. 2, 3, 4, and 5, are similar sections through modified forms, all built in accordance with the same general method, but having certain advantages which will hereafter appear.

My method was primarily designed for building the foundation of a very large wall of the type such as is commonly erected around penal institutions, and, in practical 25 use for that particular work, it has proved highly satisfactory. In this particular work, it is desirable to carry the foundation well underground in order to prevent the possibility of tunneling under the wall.

The common practice is to dig a deep trench, 30 of the width of the foundation slab or footing, and necessarily to excavate the sides of the trench back at such angles as the earth can occupy without caving in. The footing 35 is then customarily placed at the bottom of the trench so constructed, the wall is erected, and the trench is then filled in above the footing. This usual method requires a great deal of expensive excavating, and it re-

quires the presence of a spoil bank of considerable size which interferes with the progress of the erection of the wall. Furthermore, it results in a considerable body 40 of loosened earth on the two sides of the wall into which water enters freely for some time after the wall is completed, and, in this manner, the disadvantageous results of frost are accentuated. Furthermore, in the case 45 of east and west walls, the earth on the north side of the wall will remain frozen long after that on the south side has thawed out, and in this way unequal pressure above the footing is created against the side of the

wall proper with obvious undesirable results.

My present method is designed to avoid the difficulties above suggested, and to afford a method of building the foundations which is cheaper, more expeditious, and which produces a better foundation than has heretofore been customary.

In the practice of my invention, I first dig, with an ordinary ditching machine of the type commonly in use, two parallel ditches comprehending the two cross-sectional rectangular areas 6, 7, 8, and 9, in Fig. 1. I remove the earth by successive cuts at a steep angle, whereby any given cross-section of the trench is completed for its full depth at approximately the same 50 time. These cuts approximate the vertical, although some of the ditching machines work at an angle of about 45°. Machines for doing this digging are well known and work at a low cost and at considerable 55 speed, and they are usually provided with conveyors so that the material excavated can be loaded immediately into wagons for removal. As fast as the ditching machine advances cutting the trench to its full depth, 60 it is followed up by the concrete mixer, and the concrete is poured directly into the ditch, so as to form two walls up to the level of the base of the footing slab, the level of 65 these walls being indicated by the line 10, 11, and suitable anchoring means being inserted, if desired. Thus it will be seen that the digging of the trench progresses horizontally by a series of steep cuts, each cut being immediately filled with concrete 70 approximately as soon as it is made.

A considerable number of incidental advantages are attained in this portion of the work. Obviously, forms are unnecessary under normal circumstances. The flexibility of the ditching machine is such that the depth of the trench can be varied as the work progresses so that the wall in all cases goes down to a good firm foundation. In case soft ground is encountered, the relative 75 advantages are even greater, because after the ditching machine has passed through fairly soft ground, the walls usually do not cave in immediately, but are self-sustaining for a brief period. In the use of my 80 method, the concrete is filled in so rapidly

after the passing of the ditching machine that no special precautions are necessary, providing the earth is self-sustaining for a period of, say, 15 minutes. There are thus 5 many cases where sheet piling would be absolutely necessary under prior practice where my method obviates its use.

In case small pockets of quick sand and the like are encountered, the material forming them simply caves into the ditch and is taken out by the ditching machine, leaving hollow cavities in the walls of the trenches which the concrete properly fills up, thus getting a greater degree of stability at no 10 additional expense from a pocket which would ordinarily seriously interfere with the work. In every case the scores left on the earth by the ditching machine produce 15 irregularities in the concrete which make a 20 very firm bond between the walls and the earth in which they are located.

At times the earth is so soft that the method just described cannot be carried out, but even in that case, it is possible to slip in 25 retaining boards or metal plates temporarily to hold back the earth after the ditching machine has passed, and get the concrete in so quickly as to make it unnecessary either to pump or put in coffer dams or retaining 30 walls. As soon as the concrete is poured, these temporary plates can be withdrawn, the concrete comes into immediate contact while still soft with the earth.

As soon as the vertical walls, indicated in 35 the drawings by the characters 12 and 13, are poured, the remainder of the excavation can be done, this consisting of the earth represented by the cross-sectional rectangle 6, 7, 14, 15. This can be done in any desired 40 manner, is relatively small in quantity, and the earth thus removed can usually be profitably employed in refilling. When this is done, the slab 16 is poured, and for this work, as well, no forms are necessary, unless 45 the ground is very soft in which case a temporary support may be necessary along the outer edges where there may have been a slight caving in on top of the finished walls 12 and 13. This completes the foundation, 50 and the wall section can be erected thereon in the usual manner. The foundation produced is of very great strength, more particularly because the body of earth between the side walls 12 and 13 and beneath the 55 footing 16 is confined thereby, and even if inherently of very soft material, is incompressible and, therefore, acts as a perfectly solid body. It is furthermore to be noted that this body of earth has been undisturbed 60 by the operation and is, therefore, not liable to settle. Furthermore, the foundation has its greatest support at the sides where it is most needed if any lateral pressure is to be encountered. The process herein described 65 can be carried on even in the coldest weather

because the trenches can be filled up with concrete before the sides thereof have time to freeze, and the concrete is thereafter protected by the undisturbed earth banks. These walls, when completed, prevent frost 70 and water from getting under the footing slab 16, so that this can be safely located very close to the surface of the ground. If openings are required through the walls, the frames therefor can be placed in position 75 immediately after the passage of the ditching machine and before the concrete is poured. Obviously, if additional lateral support is required, suitable lateral spaces can be cut in the sides of the trenches after 80 the ditching machine has passed, and when the concrete is poured there will thus be formed piers or pilasters.

Figs. 2 and 3 illustrate modifications in the construction in which the footing slab 16 85 is replaced by an arch, that in Fig. 2 being preferably built of masonry and that in Fig. 3 being of masonry or concrete. In the form shown in Fig. 4, the wall erected upon the foundation is to one side, such as 90 might be employed in a retaining wall.

In any or all of the structures thus formed, the material between the walls 12 and 13 can be excavated so as to form a tunnel, and my method thus forms a peculiarly simple 95 and cheap method for building tunnels. If desired, the same general method can be employed in the construction of building walls, basements, and the like, in which case the walls will be built as described, and the 100 space between them thereafter excavated. In case very thick underground walls are required, beyond the capacity of the ditching machine, it is possible to build two parallel 105 walls, and when the concrete therein has set, to excavate the intermediate space and fill that also with concrete. In this way, the lateral walls serve to prevent the caving in of soft ground, and can thus be used in place of coffer dams.

In the form of construction shown in Fig. 5, a series of parallel trenches are cut as described and each is filled in with concrete, the slab being built thereon. By this means, any degree of support can be afforded for 115 the slab, and extensive and very firm foundations can be built with great rapidity. This method is desirable in the building of foundations for very heavy walls, or for floor foundations where heavy machinery is to 120 be carried, and it is believed to be especially advantageous in the rapid construction of concrete emplacements for artillery.

I realize that considerable variation is possible in the details of this construction 125 without departing from the spirit of my invention; therefore I do not intend to limit myself to the specific form herein shown and described except as pointed out in the following claims, in which it is my inten- 130

tion to claim all the novelty inherent in the construction as broadly as is permitted by the state of the art.

What I claim as new and desire to secure 5 by Letters Patent is:—

1. The method of constructing foundations for walls which consists in excavating a trench by removing the earth progressively along the trench and by successive 10 cuts at a steep angle, whereby any given cross-section of the trench is completed for its full depth at approximately the same time, filling each cut with concrete as it is excavated, permitting the concrete to set in immediate contact with the undisturbed 15 earth sides of the trench, and erecting a wall thereon.
2. The method of constructing foundations for walls which consists in excavating a trench by removing the earth progressively along the trench and by successive 20 cuts at a steep angle, whereby any given cross-section of the trench is completed for its full depth at approximately the same time, and before the walls of each cut have had time to cave in, filling each cut with concrete, permitting the concrete to set in immediate contact with the undisturbed 25 earth sides of the trench, and erecting a wall 30 thereon.

3. The method of constructing foundations for walls which consists in excavating two parallel trenches by removing the earth

along the trenches by successive cuts at a steep angle, whereby any given cross-section 35 of the trenches is completed for its full depth at approximately the same time, filling the same with concrete and permitting the concrete as they are excavated to set in immediate contact with the undisturbed 40 earth sides of the trenches, a section of undisturbed earth being left between the trenches, and after the concrete in the trenches has set, laying across the two walls formed thereof a slab supported by and in 45 contact with the undisturbed earth therebetween, and erecting a wall thereon.

4. The method of constructing foundations for walls which consists in excavating two parallel trenches, that is to say, by removing the earth progressively along the trench by successive cuts at a steep angle, whereby any given cross-section of the trench is completed from top to bottom substantially 50 at the same time, filling each cut 55 with concrete as they are excavated, leaving a section of undisturbed earth between the trenches, and after the concrete in the trenches has set, laying a slab across the two walls formed thereof and in contact 60 with and resting upon the undisturbed earth, and erecting a wall thereon.

In testimony whereof, I have hereunto set my hand this 10th day of October 1918.

HENRY W. TOMLINSON
